UNITED STATES PATENT OFFICE.

THOMAS CREBBIN, OF BRIDGEPORT, ALABAMA.

BASKET-MAKING MACHINE.

SPECIFICATION forming part of Letters Patent No. 604,457, dated May 24, 1898.

Application filed June 4, 1897. Serial No. 639,437. (No model.)

To all whom it may concern.

Be it known that I, THOMAS CREBBIN, a citizen of the United States, residing at Bridgeport, in the county of Jackson and State of 5 Alabama, have invented a new and useful Basket-Making Machine, of which the following is a specification.

My invention relates to receptacle-making machines, and particularly to those adapted 10 for use in the manufacture of baskets of various kinds—such as handleless vegetable and fruit baskets, covered and uncovered market-baskets, bail-handled picking-baskets, bushel grain-baskets, and the like; and 15 the object in view is to provide a simple and efficient construction and arrangement of parts whereby baskets and similar receptacles may be folded or shaped from plaited mats or from other suitable material, such as thin 20 staves, and whereby the bands or hoops necessary for holding the mat or staves in proper position may be applied and secured automatically, all parts of the receptacle being visible 25 throughout the operation to provide for the detection of flaws either in the material or the workmanship, and thus avoid the inconvenience and loss of time incident to proceeding with the operation of completing an imperfect article, as when the same is concealed during 30 the process of construction.

Further objects and advantages of this invention will appear in the following description, and the novel features thereof will be particularly pointed out in the appended 35 claims.

In the drawings, Figure 1 is a side view of a machine constructed in accordance with my invention, the folder being shown closed. Fig. 2 is a partial longitudinal section of the same, 40 showing the folder open with the detaching-arms in their spread or inoperative position and the anvil extended. Fig. 3 is a partial longitudinal section showing the folder with the detaching-arms in operative position and 45 the anvil retracted. Fig. 4 is a partial end view showing the means for actuating the feeding devices. Fig. 5 is a vertical transverse section on the line 5-5 of Fig. 1. Fig. 6 is a detail view in perspective of the means 50 for adjusting the friction-wheel to actuate the folder. Fig. 7 is a detail plan view of the foot-lever and attachments, showing the foot-

rest in dotted lines. Fig. 8 is an end view of the folder. Fig. 9 is a longitudinal sectional view of the anvil and coöperating parts. Fig. 55 10 is a transverse vertical section of the same on the line 10-10 of Fig. 9. Fig. 11 is a plan view of the anvil. Fig. 12 is a vertical sectional view of the stapling mechanism. Fig. 13 is a similar view taken at right angles to 60 the plane of Fig. 12. Fig. 14 is a detail view in perspective of the shears, forming one member of the stapling mechanism. Fig. 15 is a similar view of the hammer or staple-driving device, forming one member of the 65 16 stapling mechanism. Fig. 16 is a side view of a slightly-modified construction of machine wherein two devices are used coöperatively. Fig. 17 is a detail plan view of the 70 cam for operating the slide-actuating arm. 75

Similar numerals of reference indicate corresponding parts in all the figures of the drawings.

Rising from a suitable base 1 are standards 2 and 3, provided with alined slots 4, in which 75 are fitted for vertical adjustment the registering bearings 5 and 6, provided at one end with a fixed collar 5^a 6^a and at the other end with an adjustable collar 5^b 6^b. Mounted for rotary and sliding movement in said bearings 80 is a folder-shaft 7, upon which is swiveled a loose collar 8, between suitable limiting-pins 9.

Fixed to the shaft 7 is a spider 10, having a plurality of arms radiating from a hub 11, 85 these arms being provided at their outer extremities with seats 12, in which are secured folder-arms 13, having beveled extremities, as shown at 14, connected by a band 13^a and contiguous shoulders 15, formed by reducing 90 the outer portions of the arms. The spider and folder-arms constitute one member of the folder for coöperation with a second member, consisting of a form 16, this form having a hub extended to form a sleeve 17, which is 95 fitted upon a spindle 18, extending horizontally from an upright 19, in alinement with the folder-shaft 7. The form also embodies a cylindrical open-ended shell 20, equal in diameter with the receptacle to be formed 100 thereon and extended beyond the web 21, whereby it is connected with the hub to form the hollow semispherical flange 22, through a central opening 23 in which projects the ex-

tremity of the spindle 18, said spindle being reduced beyond the plane of the opening 23 to form an engaging pin 24, which fits in a socket 25 in the hub of the spider.

5 The shell of the form is provided contiguous to its open end with a plurality of spaced openings 26, and said flange terminates in a circumferential enlargement or collar 27, having interior ratchet-teeth 28.

10 29 represents a feed-shaft mounted in suitable bearings in the uprights 19 and a similar adjacent upright 19^a and carrying a feed-arm 30, to which is pivoted a feed-pawl 31 to engage the ratchet-teeth on the form and 15 thereby impart a step-by-step rotary movement to said form during the oscillation of the feed-arm. The feed-arm is preferably slotted, as shown at 32, to provide for adjustment of the pawl with relation thereto to suit 20 forms of different diameters.

Oscillatory movement is imparted to the feed-shaft by means of a reciprocating plunger-stem 33, mounted in suitable bearings in the upright 19^a and carrying a pin 34, which 25 engages a slot 35 in a lateral arm 36 on said feed-shaft, and reciprocating movement is imparted to said plunger-stem by means of a continuously-operating driving-shaft 37, having a crank-disk 38, and a link or pitman 39 connecting said plunger-stem with the crank-disk.

The plunger or stapling-hammer 40, which is fixed to the upper end of the stem 33, is provided with a hammer-post 41, operating in 35 a staple-guide 42 at the front end of a presser-arm 43, a presser-roll 44 being mounted upon a horizontal axis in a bifurcation 45 in the presser-arm and being adapted to hold an exterior band of a basket or receptacle in contact with the outer surface of the mat contiguous 40 to the plane of the enlargement or collar 27 of the form during the rotation of the form, and said staple-guide being adapted to receive staples to be driven by the hammer through 45 said band and mat in the operation of securing the former to the latter.

From the foregoing description it will be understood that the folder receives an intermittent or step-by-step rotary movement in 50 a uniform direction during the operation of the machine, the movement thereof occurring during the upward reciprocation of the plunger-stem 33, and hence during the elevation of the hammer, whereas during the downward or operative movement of the hammer the folder and form remain stationary, the feed-pawl 31 slipping idly in a rearward direction over the succeeding ratchet-teeth of the form.

55 60 In connection with the fastening or stapling mechanism I employ an anvil to accomplish the clenching of the inner end of the staple-clip, nail, or other fastening device which may be used to secure the parts of the receptacle together. In the construction illustrated the anvil 46 is bifurcated to form parallel depending legs 47, which operate in suit-

able vertical guides 48 in a horizontal anvil-support 49, the upper end of said anvil being adapted to pass through the openings 26, hereinbefore described, which are provided in the shell of the form for this purpose, and the elevation of the anvil at the proper intervals—namely, during the descent of the hammer—is accomplished by means of an actuating-slide 50, mounted horizontally in said anvil-support 49 and provided with a beveled or cam face 51, formed on a reduced tongue 52 at the front end of the slide. This tongue operates in the interval between the depending legs 47 and the anvil, and the beveled or cam face 51 thereof engages the shoulder 53, which is formed between said legs at the lower end of the body portion of the anvil. The upper side of the tongue 52 forms a horizontal rest by which the anvil is supported during the driving of the staple or nail.

The anvil is preferably provided with a vertical seat 54, in which is removably fitted a hollow die 55, said die being provided with a downwardly reduced or tapered bending-seat 56 to receive the lower extremities of the staples when they have been driven through the wall of the basket or receptacle, the downward convergence of the walls of the seat 54 serving to bend the points of the staple inwardly or toward the center of the seat. The end walls of the seat are also preferably inclined or beveled transversely in opposite directions to throw the points of the staple out of alignment with each other as the staple is forced downward, and the seat 56 is extended to form a plunger-guide 57, in which operates the upper end of the clenching-plunger 58. This clenching-plunger is provided with an enlargement or collar 59, arranged to operate in a cavity 60 in the die in communication with the guide 57. The tongue 52 of the actuating-slide 50 is also longitudinally slotted, as shown at 61, for the reception of a trip 62, which is pivoted at its rear end, and is adapted at its free end to ride upon a wedge block or cam 63, fixed to the floor of the guide in which the slide 50 is fitted. As the slide 50 is advanced during the downward movement 115 of the stapling-hammer the anvil is first elevated to enter the aligned opening 26 in the shell of the form to bring the upper surface of the guide in contact with the inner surface of the wall of the receptacle opposite to the 120 point at which the staple is to be driven. As the motion of the slide 50 continues it brings the plain or horizontal upper surface of the tongue 52 in contact with the shoulder 53 of the anvil, and thus forms a substantial support for 125 the anvil, whereby the downward impact of the stapling-hammer is effectually resisted. As the motion of the actuating-slide 50 still continues, the stapling-hammer has reached its operative position and has forced the staple 130 through the band and wall of the receptacle and has introduced the extremities of the staple into the bending-seat 56, the downward movement of said extremities, after entering

the seat, causing them to be bent to lie in different but contiguous planes and over the guide 57, and when the extremity of the trip 62 reaches the wedge block or cam 63 the former is elevated sharply and brought into contact with the lower end of the clenching-plunger 58, which, rising into the bending-seat 56, turns the points of the staple and forces them into the material forming the wall of the receptacle.

The means illustrated in the drawings for operating the slide 50 consists of an oscillatory arm 64, fulcrumed, as at 65, in a suitable bracket supported by the upright 19^a, the connection between the upper end of said arm and the slide being formed by a slotted fork 66 of the arm engaging a pin 67, carried by a depending ear 68 on the slide, and a push-arm 69, pivotally connected to the arm 64 at an intermediate point and having its beveled extremity arranged in the path of a cam 70 on the reciprocating stem 33. Said cam is of downwardly tapered or beveled construction and is elliptical or otherwise irregular in plan, Fig. 17, whereby by rotary adjustment of the cam upon the stem greater or less throw may be imparted to the slide 50. Said cam is secured at the desired adjustment by means of a set-screw 71.

In Fig. 2 I have shown the reciprocating member of the folder, comprising the spider and folder-arms, retracted to provide for the application to the center pin 24 of a plaited mat 72, which is designed to form the body portion of the basket or receptacle, said pin being inserted through a central perforation adapted to be formed in any convenient manner in the center of said mat. Before advancing said reciprocating member of the folder a middle hoop or band 73 is inserted between the reduced extremities of the folder-arms and is arranged in contact with the shoulders 15 thereof. The shaft 7 is then advanced to fold the mat upon the form and bring the upper edge of the mat under the presser-roll 44 and contiguous to the shoulder formed by the enlargement or collar 27. The exterior top band 74 is then applied beneath the presser-roll and the operation of the mechanism proceeds, as hereinbefore explained.

When the basket has been completed, it is necessary to remove it from the form in order to give place for a second mat, and in order to accomplish this I employ detaching or disengaging arms 75, fulcrumed, as at 76, upon the spider, or preferably upon the rear extremities of the folder-arms 13, and provided with tapered outer extremities having shoulders 77 to engage the outer edge of the basket, as illustrated in Fig. 3, preparatory to retracting the reciprocating folder member. The disengaging-arms are provided with in-turned trip extensions or fingers 78, disposed radially with relation to the shaft 7 and terminating at their inner ends contiguous thereto, whereby when the movable member of the folder is retracted, as shown in Fig. 2, the

free extremities of the trip extensions encounter a stop formed by the collar 6^b and are moved to the position indicated in said Fig. 2, thereby spreading the disengaging-arms and releasing the receptacle.

Owing to the fact that the exterior reciprocating folder member is supported by an axial shaft attached to said folder member at its outer end and thereby preventing the removal of a completed receptacle at said outer end of the member, it is necessary to remove the receptacle at the opposite or inner end after the reciprocating member has been withdrawn from operative relation with the fixed or interior folder member, and in order to accomplish the release of the receptacle after the retraction of the exterior folder member the disengaging or stripping arms must be spread or moved outwardly from the folder member upon which they are mounted, the spreading movement being communicated to said arms by means located at the outer end of the exterior folder member and contiguous to the said axial shaft by which said folder member is carried. Owing to the arrangement of the disengaging-arms and the arrangement of the means for operating the same, said means being located contiguous to the shaft by which the exterior folder member is supported, they cannot be substituted by the ordinary forms of stripper-arms known in the art and usually located within the exterior folder member to displace the receptacle from the inner folder member and then drop the receptacle for the reason, as above indicated, that in the construction disclosed herein the exterior member of the folder is mounted for reciprocation and is so constructed at its outer end, or that end which is remote from the interior folder member when the folder members are separated, as to prevent the axial removal of the receptacle in the same direction as it is forced into the exterior member. In displacing the receptacle it must be moved in the opposite direction, or toward the inner end of the exterior folder member.

As it is desirable to maintain the disengaging-arms in their spread position during the folding and construction of the basket, I preferably employ a securing device, consisting of a disk 79, mounted for partial rotation upon the shaft 7, contiguous to the hub of the spider, and provided with a plurality of radial slots or notches 80, through which the inner extremities of the trip extensions may pass. This disk is also provided with a handle or operating-arm 81, and hence after the movable member of the folder has been retracted to the position shown in Fig. 2 a slight movement of the handle or operating-arm 81 will secure the disengaging-arms in their spread position. Said arms remain in their spread position until after the folding of the blank from which the receptacle is to be formed, as shown in Fig. 1, and are released by a second adjustment of the disk 79 only after the completion of the receptacle and when it is time

for the retraction of the movable member of the folder to remove said receptacle. The displacing-arms are yieldingly held in their operative positions and are returned to said 5 positions when released by the retaining device 79 by means of actuating-springs 82.

The means illustrated in the drawings for actuating the reciprocatory member of the folder include a friction-wheel 83, having its 10 shaft 84 mounted in sliding journal-boxes 85 on the base 1 or other suitable support, whereby said friction-wheel may be arranged in peripheral contact with a friction-wheel 86, which is fixed to the driving-shaft 37, an 15 oscillatory lever 87, having its slotted extremity engaged with a lateral pin 88 on the collar 8, and a pitman 89, connecting said arm 87 with a crank-disk 90 on the spindle 84 of the friction-wheel. A slotted connection 20 is employed, as above indicated, between the oscillatory lever 87 and the collar 8, and an adjustable connection consisting of a slot 91 and a pivot-bolt 92 is employed between the pitman and said oscillatory lever. 25 Furthermore, inasmuch as the reciprocation of the movable member of the folder occurs only at such intervals as to provide for the removal of a completed receptacle and the application of a blank for a succeeding receptacle, it is desirable to employ shifting mechanism whereby the friction-wheel 83 may be arranged either in or out of contact with the friction-wheel 86, as required. An efficient 30 means for accomplishing this operation is shown in the drawings and embodies a foot-lever 93, upon which is mounted a movable stop 94, actuated by a bell-crank lever 95, the extremity of the stop being arranged normally in the path of projections or ears 96, 35 arranged on the friction-wheel 83 at diametrically opposite points, and the stops being yieldingly held in operative position with relation to said projections or ears by means of an actuating-spring 97. Mounted upon the 40 foot-lever contiguous to its free end is a tilting foot-rest or treadle 98, of which the toe portion is arranged in operative relation with the approximately horizontal arm of the bell-crank lever 95, whereby when the toe portion 45 of said rest or treadle is depressed it actuates the bell-crank lever and withdraws the stop from the path of the projection or ear with which it is engaged. Also connected with the foot-lever is a toggle-lever consisting of arms 50 99 and 100, pivotally connected at their remote extremities, respectively, to a fixed object, as a bracket 101 on the base 1, and to the sliding journal-box 85, and pivotally connected at their inner extremities to a depend- 55 ing bracket 102 on the foot-lever. Hence when a receptacle has been completed the operator moves the handle or arm 81 of the retaining device to release the trip extensions 78 and bring the displacing-arms 75 into operative 60 relation with said receptacle and at the same time the toe portion of the tilting foot-rest is depressed to disengage the stop

94 from the projection or ear 96 of the friction-wheel 83, and at the same time downward pressure is imparted to the lever 93 to raise the inner extremities of the toggle-arms and force the bearing 85 toward the driving-shaft sufficiently to bring the friction-wheel 83 into peripheral contact with the disk 86. Said disk immediately imparts rotary motion to the wheel 83 and moves the lever 87 to retract the reciprocatory member of the folder, and thus displace the receptacle. As soon as the rotation of the friction-wheel has commenced the tilting foot-rest is allowed 80 to resume its normal position, thus releasing the bell-crank lever 95 and allowing the stop 94 to extend into the path of the succeeding projection or ear 96 of the friction-wheel, and therefore when said friction-wheel has made 85 a complete half-revolution, thus bringing the reciprocatory member of the folder to the position illustrated in Fig. 2, or wholly retracted, the motion of the friction-wheel ceases by the contact of said succeeding projection or ear 90 of the friction-wheel with the stop 94. The receptacle is now removed from the folder-arms, the same having been released by the spreading of the displacing-arms 75, a new blank is applied to the holding-pin 24, the 95 foot-rest is again actuated to release the friction-wheel, and downward pressure is applied to the foot-lever to hold the friction-wheel 83 in contact with the friction-disk 86 until said friction-wheel has made another half-revolution, at the end of which it is again stopped by the engagement of the succeeding projection or ear 96 with the previously-released stop 94.

An important advantage of the construction herein described resides in the fact that the folder-arms, which constitute, with the spider, the exterior member of the folder, consist of narrow strips and perform their function without obstructing the view of any portion of the blank from which the receptacle is formed. In other words, the entire blank is visible from the time it is placed upon the retaining-pin of the form until the completion of the basket, and hence any flaw or defect in the construction or in the material is visible, and the receptacle upon the discovery of such defect can be removed from the machine without waiting until the completion thereof, thus saving the time which would be 110 consumed in completing a worthless article.

Any ordinary or approved construction of stapling mechanism may be used in connection with the machine embodying my invention; but in the drawings I have illustrated 115 an efficient form wherein the hammer proper, 41, is provided with a hammer-post 103, which fits in a staple-guide 104, formed by slotting a shear-blade 105, said shear-blade being arranged parallel with the hammer proper for 120 retraction thereby. The shear-blade is yieldingly held depressed or receives downward movement by means of an actuating-spring 106, and the hammer proper is provided with

a projection 107 to engage a pin 108 on the blade, whereby upward movement is communicated from the hammer to the shear-blade. The hammer-post is provided with lateral webs 109 to operate in staple-receiving grooves 110 in the staple-guide 104.

Coöperating with the hammer and shear-blade, as above described, is a staple-former 111, yieldingly held extended in the path of the hammer by means of a spring 112 and having a beveled front end forming a cam by which it may be depressed by means of said hammer. Any suitable tension devices may be employed for feeding staple-wire 113, such as a roll 114, having a ratchet 115 for engagement by a pawl 116, supported by the hammer-head, in connection with an eccentric roll 117. This staple-wire enters the hammer-head guide 118 through a suitable opening 119 and passes through a seat or notch 120 in the cam-face of the staple-former 111, whereupon when the shear-blade is depressed with the hammer the proper length of wire is detached to form the clip, and the extremities 25 of the blank thus formed are bent downwardly to lie in contact with the sides of the former. As the downward movement of the shear-blade continues the sides of the clip are forced into the clip-guides 110 below the lower extremity of the hammer-post, which is located at an interval from the lower end of the shear-blade. When the lower end of the shear-blade reaches the surface into which the clip is to be driven, its downward movement is checked, while the downward movement of the hammer continues and thus forces the staple into said material.

While in the above description I have referred to the apparatus as being adapted for driving clips and staples, it is obvious that nails may be substituted therefor and that any suitable construction of stapling apparatus may be employed in connection with the basket-forming devices, and, furthermore, that various other changes in the form, proportion, and the minor details of construction may be resorted to without departing from the spirit or sacrificing any of the advantages of this invention. Furthermore, it will be understood, although not specifically shown or described, that the disk 38 may be mounted loosely on the shaft 37 and means, as a clutch, provided for locking or unlocking the disk with relation to the shaft or to the adjacent pulley 83, so that the driving-shaft shall be left free to be engaged at will either with the staple mechanism or with the folder mechanism.

In Fig. 16 I have illustrated a double arrangement of the improved machine, wherein two are operated simultaneously, the same being arranged in opposite or reversed positions and having their folding devices connected by a bar 121, one end of which is pivoted, as at 122, to allow the rod to be broken or its parts to be deflected to remove the folders manually when the construction of a

receptacle has been completed. In order to release the folders, one of the machines—namely, that shown at A—is mounted for sliding movement in suitable ways 123, the driving-shafts 37^a of the two machines being connected by a sliding joint 124 to facilitate said movement of the machine A independently of the machine B.

Having described my invention, what I claim is—

1. In a machine of the class described, a folder having an interior form, and a reciprocating exterior member supported by an axial shaft connected with said exterior member at its outer end, radially-movable displacing-arms mounted upon the outside of the exterior member of the folder and provided at their inner sides with means for engaging a completed receptacle, and removing the latter from the form during the backward movement of the exterior member, and means located contiguous to the supporting-shaft of the exterior member, for spreading the displacing-arms to release the receptacle, the receptacle being removable from the exterior member at its inner end, substantially as specified.

2. In a machine of the class described, a folder having an interior form and a reciprocating exterior member, radially-movable displacing-arms mounted upon the exterior member of the folder and provided contiguous to their extremities with interior shoulders for engaging the edge of a completed receptacle, and removing the latter from the form during the backward movement of the exterior member, and means for disengaging said displacing-arms from the receptacle, substantially as specified.

3. In a machine of the class described, a folder having an interior form and an exterior reciprocating member, shouldered displacing-arms pivotally mounted upon the reciprocating member and provided with trip extensions, and a stop located in the paths of the extremities of said trip extensions to spread the displacing-arms when the reciprocating member is retracted, substantially as specified.

4. In a machine of the class described, a folder having an interior form, an exterior reciprocating member, pivotal detaching-arms mounted upon the reciprocating member and shouldered to engage a receptacle on the form, said detaching-arms having inturned trip extensions, a stop located in the paths of the trip extensions, whereby when the reciprocating member is retracted the detaching-arms are spread to release a receptacle, and a locking device for securing the detaching-arms in their spread position, substantially as specified.

5. In a machine of the class described, a folder having an interior form, an exterior reciprocating member, pivotal detaching-arms mounted upon the reciprocating member and shouldered to engage a receptacle on the form,

said detaching-arms having inturned trip extensions, a stop located in the paths of the trip extensions, whereby when the reciprocatory member is retracted the detaching-arms 5 are spread to release a receptacle, and a locking device consisting of a rotatable disk having slots to receive the extremities of the trip extensions and adapted to be turned to retain the latter with the detaching-arms in 10 their spread position, substantially as specified.

6. In a machine of the class described, a folder having an interior form and an exterior reciprocatory member, pivotal detaching- 15 arms mounted upon the reciprocatory member and yieldingly held in position to engage a receptacle on the form, and locking devices for securing said arms in their inoperative or spread position, substantially as specified.

20 7. In a machine of the class described, the combination with a rotary blank - folding form, and stapling mechanism having a staple-driver mounted for radial movement toward and from the exterior surface of a blank 25 on the form, of a guide disposed parallel with the axis of the form, an anvil mounted in the guide for radial movement toward and from the interior surface of the blank, in alinement with the staple-driver, whereby it may 30 be arranged in contact with the inner surface of a receptacle in the path of impact of said staple-driver, a slide mounted in said guide, and having a cam-face for coöperation with the anvil, and means for actuating the slide, 35 substantially as specified.

8. In a machine of the class described, the combination with a form and stapling mechanism having a staple-driving member operating radially with relation to the form, of an 40 anvil mounted for radial movement in alinement with the staple-driving member, means for moving the anvil to bring it in contact with the inner surface of a receptacle in the line of impact of the staple-driving member, 45 and independently-movable means carried by the anvil for bending the staple-points, substantially as specified.

9. In a machine of the class described, the combination with a form and stapling mechanism 50 having a staple-driving member, of an anvil mounted for movement in the plane of the staple-driving member and adapted to be arranged in contact with the inner surface of the wall of a receptacle to receive the impact 55 of the staple-driving member, a clenching-plunger mounted upon the anvil, and means for successively advancing the anvil and actuating said clenching-plunger, substantially as specified.

60 10. In a machine of the class described, the combination with a form and stapling mechanism including a staple-driving member, of an anvil mounted for movement in alinement with the staple-driving member and adapted 65 to be arranged in contact with the inner surface of the wall of a receptacle to receive the impact of the staple-driving member, a clench-

ing-plunger mounted in a guide arranged axially in the anvil, a slide operatively connected with the anvil, a trip carried by the slide and 70 adapted to coöperate with a cam to engage and actuate the clenching-plunger, and means for reciprocating the slide, substantially as specified.

11. In a machine of the class described, the 75 combination with a form and stapling mechanism including a staple-driving member, of an anvil movable in alinement with the staple-driving member whereby it may be arranged in contact with the inner surface of 80 the wall of a receptacle to receive the impact of said member, a die carried by the anvil and provided with a bending-seat having downwardly-convergent walls to inwardly deflect the extremities of a staple, a clenching-plunger operating in a guide communicating with the bending-seat, and means for 85 successively advancing the anvil and actuating the clenching-plunger, substantially as specified. 90

12. In a machine of the class described, the combination with a form and stapling mechanism including a staple-driving member, of an anvil movable in alinement with the staple-driving member and adapted to be arranged in contact with the inner surface of 95 the wall of a receptacle, a die carried by the anvil and provided with a bending-seat having downwardly-convergent and transversely-beveled walls, whereby the extremities of a 100 staple are bent inwardly and deflected laterally, a clenching-plunger, and means for successively advancing the anvil and actuating said plunger, substantially as specified. 105

13. In a machine of the class described, the combination of a hollow rotary form provided in its side with spaced openings, stapling mechanism having a staple-driving member, a normally stationary anvil arranged within the hollow form in alinement with the staple-driving member and capable of movement toward and from the same when an opening of the form is alined therewith, to arrange the face of the anvil in contact with the inner surface of a receptacle to receive the impact of 115 the staple-driving member, means for advancing the anvil during the operative movement of the staple-driving member, and feeding mechanism for imparting a step-by-step rotary movement to the form, to bring the openings 120 therein successively in alinement with the anvil, substantially as specified. 110

14. In a machine of the class described, the combination with a rotary form having a circumferential series of openings, stapling mechanism including a reciprocatory staple-driving member, a reciprocatory anvil adapted to be extended radially through the openings in the form and arranged in contact with the wall of a receptacle to receive the impact 125 of the staple-driving member, and a slide operatively connected with said anvil, of a driving-shaft, a stem carrying the staple-driving member operatively connected with a crank 130

on the driving-shaft, a feeding-lever operatively connected with said stem and carrying a pawl for engaging a ratchet on the form, an oscillatory arm connected with said slide, a cam arranged upon the stem, and a push-arm connected with said oscillatory arm and arranged in the path of the cam, substantially as specified.

15. In a machine of the class described, the combination with a rotary form having a circumferential series of openings, stapling mechanism including a reciprocatory staple-driving member, a stem carrying said staple-driving member and adapted to receive a continuous reciprocatory movement, an anvil adapted to be extended radially through the openings in the form and arranged in contact with the inner surface of the wall of a receptacle, and a slide for actuating the anvil, of 20 an oscillatory arm connected with said slide and provided with a push-arm, and a peripheral irregular beveled cam carried by said stem for engagement with the extremity of the push-arm, and capable of rotary adjustment to vary the throw of the push-arm, substantially as specified.

16. In a machine of the class described, the combination with a movable folder member and stapling mechanism, and a driving-shaft 25 with which the stapling mechanism is operatively connected, and having a friction-disk, of a friction-wheel operatively connected with the folder member and having movable journal-boxes whereby it may be arranged in peripheral contact with said friction-disk, a toggle-lever connecting the journal-boxes of said

friction-wheel with a fixed object, a foot-lever connected with the contiguous ends of the arms of the toggle-lever for adjusting the journal-boxes, and stop mechanism operatively connected with the foot-lever for checking the movement of the friction-wheel at intervals, substantially as specified.

17. In a machine of the class described, the combination with a movable folder member 45 and stapling mechanism, and a driving-shaft with which the stapling mechanism is operatively connected, and having a friction-disk, of a friction-wheel operatively connected with the folder member and having movable journal-boxes whereby it may be arranged in peripheral contact with said friction-disk, a toggle-lever connecting the journal-boxes of said friction-wheel with a fixed object, a foot-lever connected with the contiguous ends of the 50 arms of the toggle-lever for adjusting the journal-boxes, and stop mechanism carried by the foot-lever, consisting of a reciprocable stop-bar mounted upon the foot-lever, and a tilting foot-rest or treadle mounted upon the 55 foot-lever and operatively connected with said stop-bar, the friction-wheel being provided with projections for engagement with said stop, substantially as specified.

In testimony that I claim the foregoing as 60 my own I have hereto affixed my signature in the presence of two witnesses.

THOMAS CREBBIN.
